UNITED STATES PATENT OFFICE.

JAMES D. HARVEY, OF EVANSTON, AND JOHN W. TIERNEY, OF CHICAGO, ILLINOIS.

HUMIDIFIER FOR RADIATORS AND THE LIKE.

1,273,780.

Specification of Letters Patent. Patented July 23, 1918.

Application filed February 21, 1917. Serial No. 150,240.

To all whom it may concern:

Be it known that we, JAMES D. HARVEY, residing at Evanston, county of Cook, and State of Illinois, and JOHN W. TIERNEY, residing at Chicago, county of Cook, and State of Illinois, both citizens of the United States, have invented certain new and useful Improvements in Humidifiers for Radiators and the like, of which the following is a

specification.

The present invention has to do with certain improvements in humidifiers for radiators and the like. The humidifier herein disclosed is so constructed that it receives its water automatically from the radiator, and is thus automatically replenished from time to time. It may also serve to vent the radiator, and thus keep the same free from air at all times.

One of the objects of the invention is to provide a very simple form of device for accomplishing the foregoing as well as other results, and to provide a device of this type which can be very cheaply manufactured from a small number of parts. Also to provide a device so simple in construction and operation that it will not readily become disarranged or get out of order.

Other objects and uses of the invention will appear from a detailed description of the same which consists in the features of construction and combinations of parts hereinafter described and claimed.

Referring to the drawing:

Figure 1 shows a cross section of our improved humidifier as the same may be readily applied to a radiator of familiar form; and

Fig. 2 shows a section taken on the line 2—2 of Fig. 1, looking in the direction of the arrows.

In the drawing, we have illustrated certain of the radiator coils diagrammatically by the numerals 3 and 4, the coil 4 being the end coil to which it is customary to attach or connect the air vent. The humidifier proper comprises a longitudinal tray or trough 5 into which extends one portion of a wick or the like 6. In the particular construction illustrated, said wick extends upright from the trough, and the lower end of the wick lies within the trough.

The trough itself may be conveniently connected to or supported by one or more of the radiator coils as by means of U-bolts or straps 7 and 8.

The end of the trough 5 communicates with a chamber or compartment 9 by way of an opening 10, and as a convenient form of construction both the chamber and the trough may be formed or constructed integrally. A cap or cover 11 seats over and closes the upper end of the chamber 9 and protects the valve mechanism contained therein.

The numeral 12 designates a boss or enlargement on the end coil of the radiator into which it is customary to connect the air vent. In practising the features of our invention, we connect a pipe 13 to the radiator, and this may be conveniently accomplished by removing the air vent and connecting the pipe 13 into the boss 12. The lower end of the pipe 13 connects to the chamber 9 by a universal coupling 14. Within this coupling there is arranged a pin valve 15 which connects to one end of a lever arm 16 pivoted to a stationary part at the point 17. A float 18 on the other arm of the lever 16 serves to control the movements of said lever and thus serves also to move the pin valve 15 back and forth. Manifestly this arrangement will serve to close the valve 15 as soon as the water level within the chamber 9 has risen to the desired elevation. In this way, the supply of water to the chamber 9 and to the trough 5 will be automatically controlled by the float valve so as to maintain a substantially constant water level in the trough at all times.

It is to be observed that, with this arrangement, the float will not rise to close the valve 15 until the chamber 9 has received the desired amount of water. Consequently, the valve 15 will remain open while the radiator is being vented and the air discharged therefrom, and the valve 15 will not close until all of the air has been discharged and water delivered. It is, therefore, evident that this device will serve not only as an automatic humidifier but also as an automatic air vent.

In some cases it may be desirable to provide a hand operated valve 19 in the pipe 13, so that the humidifier may be shut off and thrown out of service. Also in other cases it may be desirable to connect an air vent of the ordinary type 20 into the pipe 13, and this may be conveniently done at any point between the radiator and the valve 19.

While we have herein shown and described

only a single embodiment of our invention, still it will be understood that we do not limit ourselves to the said construction, except as we may do so in the claim.

5 We claim:

A humidifier for a radiator comprising an elongated trough having its top open, a capillary wick standing in the trough and drawing moisture therefrom, a valve compartment at one end of the trough and in communication therewith by way of a slotted opening, the lower edge of which opening is at such an elevation as to permit the

flow of water from the valve compartment into the trough, a valve in the lower portion 15 of the compartment, a float within the compartment and operatively connected to the valve to close the same when the level of the water within the trough reaches the desired point, and a tube connecting the valve 20 with the radiator at a point of higher elevation than the valve, substantially as and for the purpose described.

JAMES D. HARVEY.
JOHN W. TIERNEY.
